United States Patent Office.

JOHN J. CROOKE, OF SOUTHFIELD, AND LEWIS CROOKE AND HENRY S. CROOKE, OF NEW YORK, N. Y.

Letters Patent No. 91,609, dated June 22, 1869.

IMPROVED HINGE.

The Schedule referred to in these Letters Patent and making part of the same.

Specification of certain Improvements in Hinges, invented by JOHN J. CROOKE, of Smithfield, in the county of Richmond, and State of New York, and LEWIS CROOKE and HENRY S. CROOKE, of the city, county, and State of New York.

Nature and Objects of the Invention.

This invention has relation to the manner of securing the pin or axis of the hinge in position, and consists of the improvements hereinafter described, by which the said pin or axis is more effectually secured from accidental or forcible displacement, and from displacement in consequence of the wearing of the parts.

Description of the Accompanying Drawings.

Figure 1 is a side elevation, showing the inside of the hinge when open.

Figure 2 is a plan or end view of the hinge.

Figure 3 is a vertical longitudinal section, made through the centre of the axis of the hinge, showing one form of construction embodying the invention, the hinge being in this figure represented as only partially finished, so as to give a more ready and clear idea of the method of manufacture.

Figure 4 is a like view of the same construction, finished.

Figure 5 is a like view, showing a modified form of construction.

Figure 6 is a like view, showing still another modification in the construction of our hinge.

General Description.

The wings A and B of the hinge are first made of wrought or malleable metal, in any of the usual forms, and this having been done, we then form a cylindrical recess in each end of the joint, and also a groove around this recess, as shown in fig. 3, which groove we prefer to make in the form of a V, the outer side thereof being cylindrical.

We then insert the pin C in position, as shown in figs. 3 and 4, leaving room in the ends of the hinge for the end-pins, or pieces D and E, as shown, which are then inserted in place.

These pins D and E are formed with round or convex heads F, like those of the common rivet, as shown, and these heads made concave on the under side, to fit into the recesses already mentioned, and bear at their outer edges upon the metal of the joint.

The length of the pins C, D, and E, when taken together, is also such as to allow for a little upsetting of the metal, in the process of securing the parts in position, without compressing the joint of the hinge.

The parts having been thus put together, we then, with a proper tool, or punch, or swage, swage down that portion of the metal which forms the inner side

of the groove above mentioned, so as to make it overhang, and secure the heads F of the parts D and E, from displacement; and at the same time, and with the same tool, we also slightly swage down the heads F of the parts D and E, so as to cause them to perfectly fill the whole diameter of the recesses, and press the metal of the wing of the hinge under the heads of these parts, closely around their shanks, as shown in fig. 4, the tool being made in such form as to accomplish all these purposes.

For greater uniformity, and greater facility of execution, we prefer to perform these operations, last described, in a press, having the proper tools inserted therein for that purpose.

In fig. 5, instead of the centre-pin being made in three pieces, C, D, and E, as shown in figs. 3 and 4, it is represented as being made in two parts, the division being in the centre; and in fig. 6 it is represented as being made in two parts, with the division near one end, and the head F formed on one end of each of these parts, as shown.

It is also obvious that the construction we have described may be still further modified, by making the pin C long enough to fill nearly the whole length of the joint, and making the heads or bosses F, separate, instead of being joined to the parts D and E, and which may be secured in place by swaging in the same manner. When such caps are used, they may be made from the punchings from the holes for the screws.

Remarks.

The construction above described secures the axis of the hinge perfectly against accidental displacement, and the making of this pin in parts allows the necessary heads to be formed upon the parts having heads before they are inserted in the joint, and the same advantage is gained by the use of metal caps without shanks, as already described.

The parts D and E may also be made ornamental at their outer ends, if desired.

This invention also has the advantages over that of simply swaging down the metal over the ordinary cylindrical joint-pin, that, by the enlargement of the diameter of the portion swaged down, it gives a great amount of metal, and, consequently, greater strength, and further, that by furnishing a shoulder inside, or toward the middle of the hinge from the part swaged, it prevents the pin from being driven out or displaced by extraneous force.

This invention may be applied to the construction of either butt or strap-hinges.

Claims.

We claim as our invention—

1. A hinge constructed with a boss, head, or shoul-

der, F, upon the end of the joint-pin, or outside thereof, sunk in a recess formed in the end of the hinge, and the metal of the joint swaged down upon or closed over said head, boss, or shoulder, substantially as hereinbefore set forth.

2. The combination, with the wings of the hinge and the joint-pin or pintle, of the bosses, shoulders, or heads, F, made separate from the axis of the hinge, or upon parts of a divided pintle, and secured in place

by swaging down the metal of the hinge upon the said bosses, shoulders, or heads, substantially as hereinbefore set forth.

JOHN J. CROOKE.
LEWIS CROOKE.
HENRY S. CROOKE.
